Primary Examiner — Deanna L Pratt(74) *Attorney, Agent, or Firm* — Birch, Stewart, Kolasch & Birch, LLP(57) **CLAIM**

The ornamental design for cabinet picture frame, as shown and described.

DESCRIPTION

FIG. 1 is a right and front side perspective view of a cabinet picture frame showing my new design;

FIG. 2 is a front elevational view thereof;

FIG. 3 is a bottom plan view thereof;

FIG. 4 is a top plan view thereof;

FIG. 5 is a right side elevational view thereof;

FIG. 6 is a left side elevational view thereof;

FIG. 7 is a rear and bottom view in the open position; and, FIG. 8 is a right and front side perspective view thereof in an open position.

The portions shown in broken lines show environmental structure only and form no part of the claimed design.
